Primary Examiner — David G Muller*Assistant Examiner* — Noah Perez(74) *Attorney, Agent, or Firm* — Greer, Burns & Crain,
Ltd(57) **CLAIM**

The ornamental design for a multi-port charging stand, as
shown and described.

DESCRIPTION

FIG. 1 is a top perspective view of the present multi-port
charging stand;

FIG. 2 is a left side view of the multi-port charging stand of
FIG. 1;

FIG. 3 is a right side view of the present multi-port charging
stand;

FIG. 4 is a front view of the present multi-port charging
stand;

FIG. 5 is a rear view of the multi-port charging stand of FIG.
1;

FIG. 6 is a top view of the multi-port charging stand of FIG.
1; and,

FIG. 7 is a bottom view of the multi-port charging stand of
FIG. 1.

The broken lines in the drawings depict portions of the
multi-port charging stand that form no part of the claimed
design.

1 Claim, 5 Drawing Sheets(56)
